Amazon.com, Momcozy Baby Nasal Aspirator, Feb. 24, 2024, <https://www.amazon.com/Momcozy-Aspirator-Electric-Portable-Rechargeable/dp/B0CPQ39SJQ/> (Year: 2024).*

Primary Examiner — Nathan M Johnston

CLAIM

The ornamental design for a baby nasal aspirator, as shown and described.

DESCRIPTION

FIG. 1 is a top, front, left side perspective view of a baby nasal aspirator, showing my new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings show portions of the baby nasal aspirator that form no part of the claimed design.
